UNITED STATES PATENT OFFICE

135,752

DESIGN FOR A DOG HARNESS

Thomas L. Curtis, Utica, N. Y.

Application June 20, 1942, Serial No. 107,270

Term of patent 7 years

To all whom it may concern:

Be it known that I, Thomas L. Curtis, a citizen of the United States, residing at Utica, in the county of Oneida and State of New York, have invented a new, original, and ornamental Design for a Dog Harness, of which the following is a specification, reference being had to the accompanying drawing, forming part thereof.

The figure is a perspective view of the dog harness, showing my new design.

The ornamentation on the opposite side of the

body portion is the same as that of the side shown. The characterizing features of the present dog harness design reside in the association, arrangement and ornamentation of the elements comprising said dog harness, specifically as shown on the drawing.

I claim:

The ornamental design for a dog harness, as shown and described.

THOMAS L. CURTIS.
